US00D709876S

(12) **United States Design Patent**
Aumiller et al.

(10) **Patent No.:** **US D709,876 S**
(45) **Date of Patent:** **** Jul. 29, 2014**

(54) **ELECTRONIC DEVICE**

(71) Applicant: **Samsung Electronics Co., Ltd.**,
Suwon-si (KR)

(72) Inventors: **Curtis Aumiller**, San Jose, CA (US);
Pranav Mistry, Cupertino, CA (US);
Chengyuan Wei, Dalian (CN)

(73) Assignee: **Samsung Electronics Co., Ltd.**,
Suwon-si (KR)

(**) Term: **14 Years**

(21) Appl. No.: **29/453,877**

(22) Filed: **May 3, 2013**

Related U.S. Application Data

(63) Continuation of application No. 29/449,656, filed on
Mar. 15, 2013.

(57) **CLAIM**

The ornamental design for an electronic device, as shown and described.

DESCRIPTION

FIG. 1 is a top front perspective view of a first embodiment of an electronic device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top rear perspective view thereof in a case where a terminal portion of the band is partially truncated;

FIG. 9 is a top front perspective view of a second embodiment of an electronic device showing our new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof; and,

FIG. 15 is a bottom plan view thereof.

The broken lines shown in the drawings illustrate portions of the electronic device which form no part of the claimed design.

1 Claim, 9 Drawing Sheets
